UNITED STATES PATENT OFFICE.

JOHN YEMIKER, OF AKRON, OHIO.

COLLAPSIBLE CORE.

1,107,397.

Specification of Letters Patent.

Patented Aug. 18, 1914.

Application filed April 19, 1913. Serial No. 762,442.

To all whom it may concern:

Be it known that I, JOHN YEMIKER, a citizen of the United States, residing at Akron, in the county of Summit and State of Ohio, have invented certain new and useful Improvements in Collapsible Cores, of which the following is a specification, reference being had to the accompanying drawings.

10 This invention comprehends certain new and useful improvements in collapsible cores or mandrels, the present invention relating particularly to a collapsible core for use in molding rubber tires or analogous articles.

15 The invention has for its primary object an improved collapsible core embodying an improved means for uniting its members or sections together without the use of bolts and nuts.

20 A further object of the invention is a simple, durable and efficient collapsible core, the parts of which may be readily assembled and held rigidly in operative relation to each other by means of an expansible ring de-

25 signed to exert a radial pressure on the core sections in an outward direction against the reaction of a rigid and continuous annulus extending around one side face of the core. And the invention also aims to generally improve devices of this class so as to render them more useful and commercially desirable.

With these and other objects in view, as will more fully appear as the description 35 proceeds, the invention consists in certain constructions, combinations and arrangements of the parts that I shall hereinafter fully describe and claim.

For a full understanding of the invention, 40 reference is to be had to the following description and accompanying drawing, in which:—

Figure 1 is a side elevation of my improved collapsible core, parts being broken away. Fig. 2 is a transverse sectional view on the line 2—2, of Fig. 1. Fig. 3 is a similar view on the line 3—3, of Fig. 1. Fig. 4 is a fragmentary view illustrating a modification hereinafter specifically referred to.

50 Corresponding and like parts are referred to in the following description and designated in the accompanying drawing by like reference characters.

The body of my improved collapsible core

is composed of a plurality of separable sections which are segmental in form and tubular. In the present instance, there are four of these sections employed, designated 1, 2, 3 and 4, although it is to be understood that the invention is not limited in this regard. 55 Any desired number of sections of the core (the section 4 in the present instance), has its ends disposed in a plane oblique to the radii of the annular body of the core, the inner portion of such section being of greater 60 length than the outer or peripheral portion, whereby the member 4 will serve in the nature of a key and may be readily moved inward out of engagement with the obliquely arranged end of the adjacent sections 1 and 65 3 when it is desired to collapse the core preparatory to removing it from the molded tire casing. The abutting ends of the sections 1, 2 and 3 may be radially disposed because these sections may be readily removed 70 from the tire casing after the key section 4 has been removed. Each of the sections which together form the body of the core, is formed on its inner side with a segmental flange, the ends of said flanges when the sections 75 are assembled, abutting against each other to constitute an annular bead 5 which is adapted to be engaged by the improved clamping means of this invention. Preferably the bead 5 is laterally extended. That 80 is, it is wider than the web 6 which joins it to the main portion of the core body, as best illustrated in Fig. 2.

In order to hold the core sections rigidly in assembled relation to each other, I form 90 the bead 5 in one side with an annular recess 7 in which is designed to fit the laterally extending flange 8 of a one piece or continuous and unbroken annulus 9, said annulus abutting against the recessed side of the 95 bead and extending inwardly within the margin of the inner wall of the bead, as clearly illustrated in Fig. 2.

Mounted within the circle of the bead 5, is an expanding member in the form of a 100 split ring 10, said ring being preferably substantially the same width as the bead, although this is not essential, and being provided on its outer surface with an outwardly projecting annular flange 11 which is designed to fit within a recess 12 formed in that side of the bead 5 where the recess 7 is also formed. It will thus be understood that 105

the annulus 9 overlaps one side of the expanding ring 10. As just above specified, the ring 10 is split and where the ends come together, or approximately so, I insert a 5 taper key or screw 12^a, the same being inserted laterally in between said ends so as to expand the ring and cause it to press the sections of the core body outwardly against the flange 8 of the continuous or rigid annulus 9. Obviously, the annulus is formed 10 with an opening 13 in registry with the split portion of the ring 10, whereby the taper key or screw or similar wedge member may be inserted.

15 Preferably, the sections of the core body are formed at their abutting ends and in the outer and inner edges thereof, with recesses 14 designed to receive dowel keys 15 for the purpose of preventing the sections from 20 having any side motion and from becoming accidentally displaced by such motion.

From the foregoing description in connection with the accompanying drawing, the 25 operation of my improved collapsible core will be apparent.

In the practical use of the device, after the sections of the core body have been assembled with their ends abutting and the dowel 30 keys 15 inserted in place, the side annulus 9 is placed in position, as is also the expanding ring 10, and the wedge member 12^a is then driven or worked into place, whereby 35 the ring 10 will be expanded and the core sections pressed outwardly into firm relation to each other and will thus be held rigidly connected one to the other by the expanding ring 10 and the correlated action of the annulus 9.

It will thus be seen that I have provided 40 a very simple construction of collapsible core, the parts of which may be very readily assembled and in a simple and efficient manner. It will be noted that the recess 7 in the side face of the bead 5 is formed at the 45 juncture of the bead with the web 6, whereby the flange 8 will lie in the same transverse plane as the shoulder which is formed at the juncture of the opposite or unrecessed side of the core and the web.

50 In that form or embodiment of my invention illustrated in Fig. 4, 6^a designates the web, 7^a the annular recess therein and 8^a the laterally extending flange of the one piece or continuous and unbroken annulus 9^a. 10^a 55 designates the split ring, 11^a the annular flange thereof and 13^a the aperture in the annulus 9^a through which the wedge pin 12^a is inserted to expand the ring 10^a. This embodiment of the device differs from that 60 illustrated in Figs. 2 and 3 by having the annular flange 8^a formed with an extension 16 fitting within the annular recess 7^a, said recess being set in from the juncture of the web 6^a and the lateral enlarged or widened 65 bead 5^a. This makes a strong construction,

leaving more solid metal in the body of the web, but it is to be understood that this form is an alternative of the other form and that both forms come within the purview or scope of my invention.

70 While the accompanying drawings illustrate what I believe to be the preferred forms of my invention, it is to be understood that the invention is not limited thereto, but that various changes may be made in the construction, arrangements and proportions of the parts without departing from the scope of the invention, as defined in the appended claims.

What I claim is:—

80 1. A collapsible core including a plurality of separable segmental sections adapted to abut one against the other to form the circular body of the core, said sections being together provided with an inwardly extending annular bead, said bead being formed in one side with an annular recess, a rigid annulus abutting against the recessed side of the bead and formed with a laterally projecting annular flange fitting in said recess, 90 an expansible split ring mounted within the circle of the bead and engaging the same, and means for expanding said ring.

2. A collapsible core including a plurality of segmental sections arranged in abutting relation to each other whereby to produce a circular structure, said sections being together formed with an inwardly projecting annular bead, said bead being formed in one side with an annular recess, a rigid and unbroken annulus engaging one side face of the bead and formed with a laterally projecting annular flange fitting in said recess, 95 an expansible split ring fitting within the circle of said bead, and means for expanding said ring against the bead, the annulus projecting inwardly over and contacting with one side face of said ring.

100 3. A collapsible core, including a plurality of separable segmental sections arranged in abutting relation to each other to produce a circular structure, said sections being together provided with an inwardly projecting annular bead, said bead being formed in one side with outer and inner annular 110 grooves, an annulus engaging the recessed side of the bead and formed with a laterally projecting annular flange fitting within the outer groove, an expanding ring formed with an outwardly projecting flange fitting 120 within the inner groove, and means for expanding said ring.

115 4. A collapsible core including a plurality of separable segmental sections arranged in abutting relation to each other, whereby to 125 produce a circular structure, said sections being together formed with an inwardly projecting annular bead, said bead being formed in one side with an annular recess, a rigid and unbroken annulus engaging one 130

side face of the bead and formed with a laterally projecting annular flange fitting in said recess, an expandible ring fitting within the circle of said bead, and means for expanding said ring against the bead, the bead being formed with a groove and the ring with an outwardly projecting flange fitting within said groove.

5. A collapsible core including a plurality of separable segmental sections arranged in abutting relation to each other, said sections being formed with an inwardly projecting annular bead, the bead being formed in one side with outer and inner annular recesses, 10 an annulus engaging the recessed side of the bead and formed with a laterally projecting annular flange fitting within the outer recess, an expandible split ring mounted within the circle of the bead and engaging the same 15 and formed with an outwardly projecting annular flange fitting within the inner recess, the annulus overlapping the flanged side of the split ring and formed in registry with the ends of said ring, with an opening, 20 and a wedge member adapted to be inserted 25

through said opening in between the ends of the ring to expand the latter.

6. A collapsible core including a plurality of separable segmental sections arranged in abutting relation to each other to produce a 30 circular structure, said sections being together formed with an inwardly projecting annular bead, said bead being formed with outer and inner annular side grooves, an annulus engaging the side of the bead and 35 formed with a laterally projecting annular flange fitting within the outer groove and extending inwardly within the margin of the inner wall of the bead, an expandible ring fitting within the circle of the bead and 40 formed with an outwardly projecting flange fitting within the inner groove, and overlapped by said ring, and means for expanding said ring.

In testimony whereof I hereunto affix my 45 signature in the presence of two witnesses.

JOHN YEMIKER.
